UNITED STATES PATENT OFFICE.

JOHN J. SULLIVAN, OF CINCINNATI, OHIO.

INKING ATTACHMENT FOR BED AND PLATEN JOB-PRINTING PRESSES.

Application filed December 18, 1924. Serial No. 756,753.

To all whom it may concern:

Be it known that I, JOHN J. SULLIVAN, a citizen of the United States, residing at the city of Cincinnati, in the county of Hamilton and State of Ohio, have invented certain new and useful Improvements in Inking Attachments for Bed and Platen Job-Printing Presses, of which the following is a specification.

10 The object of my invention is to provide an inking attachment for bed and platen job printing presses which will allow for the even, uniform, and constantly efficient distribution of the printing ink, preparatory to placing the same upon the type or form, ready for the printing operation itself.

I dispense with the usual ink carrying circulating disc well known in the art in this form of printing presses, and provide a plate 20 usually semi-cylindrical in contour which I call a vibrating distribution plate, which vibrates forwardly and backwardly upon which ink is deposited and I provide means for thoroughly, evenly and uniformly distributing the ink thereon, forming a film of ink thereon which will produce a film of ink of the same density and thickness, throughout, which is transferred to the inking rollers which place the same upon the 30 type or form, ready for the printing operation itself, insuring an even and uniform application of ink to the type, plate or cut being used.

In order to thoroughly distribute the ink 35 and place it uniformly and evenly upon the distribution plate, my distribution plate vibrates forwardly and backwardly and presses against the rollers which carry the ink, these rollers remaining stationary and in this manner the distribution plate by its vibrating action takes the proper amount of ink off of the rollers, hence it is evenly distributed on said plate.

40 My attachment is simple, highly efficient in operation and dependable for uniform work, possessing great utility.

It is a well known fact that in order to do a good job of printing, the ink must be evenly and uniformly distributed so that the 45 printing itself will be of a standard, uniform, and even appearance upon the paper upon which the printing is done, so as to be pleasing to the eye and show good workmanship in its appearance.

50 With my attachment I overcome any de-

fects now present in the bed and platen printing presses now used, as to the proper distribution of the printing ink.

The various features and advantages of my invention will readily become apparent 60 from a perusal of the following specification and claims.

In the accompanying drawing forming part of this specification:

Fig. 1, is a view in elevation of a printing 65 press, showing my device in position,

Fig. 2, is a rear view in elevation of my device,

Fig. 3, is a side elevation of one side of 70 the device,

Fig. 4, is a view in elevation of the other side of my device,

Fig. 5, is a plan view of the device, and

Fig. 6, is an enlarged plan view of the cam lever and its connecting working parts. 75

In carrying out my invention as shown in the drawing, I illustrate an outline of a bed or platen job printing press in order to better describe my device or attachment.

Located in the side frames 1 of the printing press, is the shaft 2, on which I pivotally mount one end of the roller arm 3, the other end is mounted to an arm 4 mounted on a rock shaft 5, which is supported by the beams 6, the beams being in turn, held 85 securely in the rocking bed 7 of the printing press. Mounted on said shaft, at both ends, are the side plates 8, 8', and at their upper edges 9 I place the semi-cylindrical, vibrating curved ink distributing plate 10. 90

On both sides of the distribution plate 10 I place the curved brackets or guards 12, 12, one end of which is fastened in the beams 6, at point 13, the opposite end being fastened to the rocking bed 7 of the printing 95 press, at the point 14.

On the brackets 12, I place the auxiliary brackets 15, in which I mount the shaft 16; at one end of said shaft I place the roller link 17 and the opposite end of said shaft 16 100 is mounted in one arm of cam lever 21 which link 17 and lever 21 carry the ink feed roll 19, which is mounted on the shaft 20, one end of which shaft being mounted in the cam lever 21, which is pivotally mounted on 105 the stud shaft 22, supported by the beam 6. In the upper extremity of the arm 23 of the cam lever 21, I pivotally mount the cam roller 24, which engages the cam 25, mounted on the side 8'. A recessed portion 26 of 110

the cam 25 is for the purpose of allowing the lever 21, with its feed roll 19 to reach up and take a supply of ink, when the distribution plate 10 and sides 8 and 8' are in the position shown in Fig. 4.

In the side 8, I place the pin 27 which engages the slot 28 in lever 29 and in the other end of the lever 29 I mount one end of the rocker arm 30 and at the other end of said rocker arm I pivotally mount the pawl 31; this pawl engages the ratchet 32, which is mounted on one end of the shaft 33, said shaft being securely mounted in the rocker arm 30, near its center.

15 The shaft 33 also carries the ink roll 34 which is located in the ink fountain 35.

10 Mounted on the brackets or guards 12 are the ink distributing rolls 36, 37, 38 and 39 and between these rolls is the agitator vibrating roll 40. These rolls are of the usual 20 form now well known in the art, and need not be further described.

15 On the ink fountain 35 I provide the adjusting screws 41, they regulating the supply of ink and as they are well known in the art, they need not be further set forth.

20 I will now set forth the operation of my device or attachment as connected to a bed or platen job printing press. As the rocking bed 7 of the printing press rocks backwardly and forwardly, the lever arm 3 rocking on the shaft 2, which is held stationary in the side frames 1, of the printing press causes the distribution plate 10 and the side 25 plates 8 and 8' to rock back and forth on their shaft 5 by reason of small arm 4 being connected to the lever 3. It will be seen that when the bed 7 moves backwardly and forwardly with one end of lever 3 held stationary and the other end connected to the arm 4, mounted on shaft 5, said shaft 5 being carried by the bed itself, a rocking action will take place, with the distribution 30 plate 10. In other words, said plate 10 will be vibrated.

35 As the distributing plate 10 vibrates or rocks back and forth, the plate 8 carrying the pin 27, which riding in slot 28, after having reached its limit of travel, said pin 40 27 will carry with it the lever 29, causing the pawl 31 to ride backward through medium of link 30 so that when the distribution plate 10 returns, and the pin 27 returns to its limit of travel at the opposite end of the slot 28, it carries said lever 29 with it, to a predetermined point, causing the ratchet 32 to revolve the ink roll 34, through the 45 medium of the lever 30 and the pawl 31.

50 As the distribution plate 10 rocks or vibrates back and forth the cam roller 24 engaging cam 25 at the recess 26 allows the feed roll 19 to take its supply of ink from the intermediate feed roll 42, which, in turn, distributes it over the plate 10, when the 55 roller 24 passes out of the recess 26 on the

cam 25, allowing the feed roll 19 to contact with the vibrating distribution plate 10 as said plate passes underneath the roller 19. In order to keep the even distribution of ink on plate 10, I also provide the agitator rolls 36, 37, 38, 39 and 40. These rolls are well known in the art and need not be further described.

60 The rollers 50, there being three in the present instance, are the ones which take the ink off of the distribution plate 10 and transfer it to the form having the type or printing matter thereon, see Fig. 1. The distribution plate 10 vibrates forwardly and backwardly and vibrates backwardly to receive a 65 fresh supply of ink and then moves forwardly and as it moves forwardly the rollers 50 which place the ink upon the form carrying the type moves up on its face to receive the fresh ink, and while said rollers 50 are moving downwardly to place said ink upon the form carrying the type, the distribution plate 10 is moving backwardly to receive a fresh supply of ink and this 70 movement is kept on as long as printing is 75 being done.

75 Through the medium of adjusting screws 41 more or less ink can be allowed to pass upon the distribution plate 10 as desired and in this manner a film of ink upon said distribution plate may be heavier at one point than at another. This being the case when more ink is desired to be placed upon the printing form at certain places. For example, if a sheet had to be printed with 80 light small type at one end and having large and dark type at the opposite end of said sheet, then I would place more ink on the distribution plate at the point where the large type would come on the sheet when 85 printed and less ink where the small letters would come, during the printing process; a better, superior and more workmanlike job would result, and the appearance of the 90 printing enhanced. The ink would be evenly 95 distributed under these conditions, except that more ink would be distributed at one point than at the other, but it would be distributed evenly for this job and every separate sheet printed. From the foregoing, it 100 will readily become apparent that various 105 colors may be applied to various areas extending longitudinally of the elongated face of the distribution plate, whereby a multi-color printing job may be handled on a job 110 printing press, care need only be taken to 115 prevent overlapping of colors.

120 The distribution plate 10 may be of any other form or contour than herein specifically shown and described and I may support it in position in any other manner to form and carry out the vibrating plate as described.

125 The form herein shown of the attachment is a preferred one, but I may deviate from 130

the same and modify it, so long as it falls within the scope of this specification and claims.

What I claim as new and my invention and desire to secure by Letters Patent is:

1. A bed and platen job printing press comprising a press frame, a rocking bed pivotally mounted on the frame, a shaft extending transversely of the rocking bed, a 10 materially curved distributing plate mounted for oscillation on the shaft, means for applying ink to one end of the distributing plate, distributing rollers carried by the rocking bed for movement therewith, the 15 distributing plate adapted upon movement about its pivotal mounting to move relative to said distributing rollers for distributing ink longitudinally of the distributing plate, other rollers for receiving ink from the distributing plate and delivering the ink to the type form, and means for moving the rocking bed and the distributing plate about their respective mountings. 20
2. A bed and platen job printing press comprising a press frame, a rocking bed pivotally mounted on the frame, a shaft extending transversely of the rocking bed, a distributing plate mounted for oscillation on the shaft, means for applying ink to one end 25 of the distributing plate, distributing rollers carried by the rocking bed for movement therewith, the distributing plate adapted upon movement about its pivotal mounting to move relative to said distributing rollers for distributing ink longitudinally of the distributing plate, other rollers for receiving ink from the distributing plate and delivering the ink to the type form. 30
3. A printing press of the class described, comprising a press frame having a bed part, a shaft, said shaft extending transversely of the said bed part, a distributing plate, mounted for oscillation, relative to said shaft, said distributing plate oscillating when said shaft turns, means for applying ink to one end of said distributing plate, distributing rollers, the distributing plate adapted upon movement to move relative to said distributing rollers, for distributing ink longitudinally of the distributing plate, other rollers for receiving ink from the distributing plate, and delivering said ink to the type form in the press. 35

In testimony whereof, I affix my signature at Cincinnati, Ohio, this 16th day of December, 1924.

JOHN J. SULLIVAN.
